[57] CLAIM

The ornamental design for a tower supported cable stay roof structure, as shown and described.

DESCRIPTION

FIG. 1 is a perspective view of the structure; FIG. 2 is a side elevational view of the structure; FIG. 3 is a front elevational view of the structure; and FIG. 4 is a top plan view of the structure. The broken line showing a building is for illustrative purposes only and form no part of the claimed article.

FIG. 1.**FIG. 2.****FIG. 3.****FIG. 4.**
